[57] CLAIM

The ornamental design for a bed leg cushion, as shown and described.

DESCRIPTION

FIG. 1 is a front elevational view of the bed leg cushion of the present invention;

FIG. 2 is a rear elevational view of the bed leg cushion of FIG. 1;

FIG. 3 is a left side elevational view of the bed leg cushion of FIG. 1;

FIG. 4 is a right side elevational view of the bed leg cushion of FIG. 1;

FIG. 5 is a top plan view of the bed leg cushion of FIG. 1; FIG. 6 is a bottom plan view of the bed leg cushion of FIG. 1; and,

FIG. 7 is a top, front elevational view in an alternate position of the bed leg cushion of FIG. 1.

The broken lines are shown for illustrative purposes only and form no part of the claimed design.
